UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF CRACKING PETROLEUM OIL

Application filed December 10, 1920, Serial No. 429,609. Renewed June 9, 1926.

This invention relates to improvements in process for cracking petroleum oil, and refers more particularly to a process in which oil is subjected to action of heat and pressure and simultaneously to the action of an incondensable gas such as hydrogen chloride introduced into the charging line and producing thereby light oils and hydrocarbon chlorides.

10 In the drawing the single figure designates a view partly in side elevation and partly in vertical section of the apparatus for carrying out the invention.

Referring to the drawing, 1 designates the 15 furnace, having combustion chamber 2, burner 3, stack 4. In the furnace is mounted the heating coil 5, which takes the form in the present instance of a continuous coil of say four-inch pipe several hundred feet in 20 length. The inlet side of the coil is connected to the charging pump 6 by means of feed line 7. This charging pump 6 is in turn connected to any suitable raw oil supply, as for example, an asphaltic fuel oil or an asphaltic crude, such as Mexican or California 25 heavy crudes, or heavy Texas or other Mid-continent fuel oils. The delivery side of the coil 5 is connected by insulated transfer line 8, having throttle valve 9, to an expansion 30 chamber 10, preferably located outside of the fire zone, and taking the form in the present instance of a large drum, as for example, a horizontal cylinder 8 feet in diameter and 50 feet long. This expansion chamber is provided with residue draw off pipe 11, having 35 throttle valve 12, and with vapor outlet pipe 13, which pipe 13 extends into the lower part of a dephlegmator 14, and is provided with a spaced cap member 15, the arrangement being such as to permit the vapors to readily 40 enter the dephlegmator, but preventing the reflux condensate from falling back into the vapor chamber. This dephlegmator 14 is provided with spaced baffle members 16, and is shown as inclined at an angle of say 45 degrees. It is also provided with a vapor 45 outlet pipe 17, having throttle valve 18, and leading to condenser coil 19, seated in condenser box 20. The lower end of the coil is 50 connected by pipe 21, having throttle valve

22, to the top of the receiver 23. This receiver 23 has pressure gauge 24, liquid level gauge 25, and liquid draw off pipes 26 and 27, controlled by throttle valves 28 and 29 respectively. It is also provided with an incondensable gas outlet pipe 30, having throttle valve 31. The pipe 30 may be connected to a suitable supply tank, not shown, of hydrogen chloride gas. The reflux condensate is drawn off the bottom of the dephlegmator 60 through pipe 32, having throttle valve 33, which pipe 32 leads back to the feed line 7.

As a feature of the invention, there is introduced into the feed line 7 through pipe 34, having throttle valve 35, hydrogen chloride gas under pressure. As the process proceeds, the fresh hydrogen chloride gas may be mixed with the gas coming out of the pipe 30, and returned to the system. By means of the present process, hydrocarbon chlorides will be produced and also light oils, such as gasoline, kerosene or the like. Carrying out the process, the hydrocarbon oil may be heated to a temperature in the heating coil of say 750 degrees F., more or less, subjected to a pressure of say 100 pounds. It will be understood that the pressure may vary widely with the result to be obtained in the kind of oil being treated, and of course this also applies to the temperature.

80 I claim as my invention:

A process of cracking petroleum oil where- 85 in hydrocarbon chlorides are formed con- sisting in continuously passing a stream of oil through a cracking coil disposed within a furnace, in subjecting said oil while in the furnace to a cracking temperature while maintained under a superatmospheric pres- 90 sure, in introducing said oil to an expansion chamber where vaporization occurs, in con- densing the vapors and collecting the con- densate and gases in a receiver, and in con- tinuously admitting to the stream of oil 95 passing to said cracking coil incondensable gases from said receiver mixed with hydro- gen chloride for passage through said crack- ing coil.

GUSTAV EGLOFF.
